CLAIM

The ornamental design for the "baking soda holder for use in a refrigerator", as shown and described.

DESCRIPTION

FIG. 1 is a perspective view of a baking soda holder for use in a refrigerator, showing my new design;

FIG. 2 is a side elevational view thereof, the opposite side being a mirror image;

FIG. 3 is a front elevational view thereof;

FIG. 4 is a back elevational view of the baking soda holder;

FIG. 5 is a top plan view of the baking soda holder; and,

FIG. 6 is a bottom plan view of the baking soda holder.
